UNITED STATES PATENT OFFICE

LAFAYETTE D. PICKERING, OF COLUMBUS, OHIO, ASSIGNOR TO THE COLUMBUS DENTAL MANUFACTURING COMPANY, OF COLUMBUS, OHIO, A CORPORATION

ARTIFICIAL TEETH

Application filed January 18, 1930. Serial No. 421,764.

There has, in recent years, been quite an active development in interchangeable teeth with integral root sections, and this development has necessarily resulted in a similar activity in the supports, backings or bridges for such teeth designed for the particular construction of the tooth which is to be mounted thereon.

In many of the structures it may be observed that the joint between the holding device on the support and the recess in the tooth is exposed to the secretions of the mouth. Although this joint is commonly filled with cement when a dental bridge is completed and anchored in a patient's mouth, yet in the course of time the cement has a tendency to disintegrate in the saliva thus affording an objectionable harbor for bacteria and small particles of food. Those persons familiar with the art understand that micro-organisms which gather in these harbors are constantly of more or less danger to the health of the individual. Further, the small particles of food that gather in these tiny recesses afford a good media in which the bacteria may grow and multiply.

Further, exposed joints are sometimes objectionable, particularly to highly sensitive people, in that the tongue frequently comes in contact with the exposed joint and unless the joint is sufficiently accurate in its fitting of parts and the general surface contour substantially even and continuous the nervous system of the user becomes disturbed. This is particularly true where cements have disintegrated in the secretions of the mouth to the extent that open joints present uneven and broken contours to the tongue. In such instances the user sometimes becomes so disturbed over the condition that it is necessary to remove the bridge and supplant it with a new structure. This represents loss of time and money to both the dentist and the patient.

The object of my invention is to provide an interchangeable tooth with integral root, and a backing or support which will present a smooth lingual face. In the past it has been common for post holes and grooves to enter the porcelain tooth from the lingual side and

when assembled and functioning in combination with a metal backing the orifice of these retentive grooves, or post holes, is directly exposed to the action of the saliva. In my invention I propose to so position the post hole and retentive grooves that the backing completely covers and seals them so that they are not directly exposed to the oral secretions.

In the drawings:

Figure 1 is a vertical sectional view of my improved tooth with full contour backing applied.

Figure 2 is a side elevation of the tooth with the backing removed.

Figure 3 is a lingual elevation of Figure 2.

Figure 4 is a top plan view of the backing.

Figure 5 is a view similar to Figure 1 except that the post and its hole are inclined to the long axis of the tooth.

Figure 6 is a side elevation of the tooth with the backing removed.

Figure 7 is a side elevation of a posterior tooth embodying my invention.

Figure 8 is a vertical section of Figure 7 with a full contour backing attached.

Figure 9 is a side elevation view of the backing, the dotted lines showing angular changes of planes in which the apron of the backing may be set.

The reference numeral 5 designates the tooth body having an integral root section 6, there being a lingual overhang portion 7, the occlusal end of which is provided with two flat and comparatively broad bearing faces or seats 8 and 9 formed in different planes extending at a substantial angle to the long axis of the tooth, as clearly shown in Figure 2. The seat 8 is slightly inclined toward the gingival end of the tooth to facilitate the removal of the tooth from the backing or support. Both of these faces 8 and 9 are, when the tooth is mounted in its support below the point of contact between the gum and the tooth so that the gum is only in contact with the porcelain. A seat or bearing face 10 extending from side to side of the tooth extends from the seat 8 to the seat 9, and is intersected with a mortise 11 extending labially into the tooth body beyond the labial end of the seat 9, said mortise being

opened to the seat 9 by means of a slot 12 of less diameter than the mortise.

The backing or support 13 engages the bearing face 14 of the tooth, and is provided at its gingival end with a broad flat support 17 which is designed to extend from side to side of the tooth and engage the bearing face 9 of the tooth, said support 17 being provided with a web 15 and a post 16 both extending gingivally from the support 17 as clearly shown in Figure 1.

From the above it will be seen that the tooth and backing have complementary bearing surfaces, and that the two flat comparatively broad bearing faces 8 and 9 afford a maximum support for the tooth disposed transversely of the tooth to protect the porcelain tooth structure not only against stresses in the direction of the long axis of the tooth, but these broad flat bearing faces support the tooth against twisting strains and stresses, while the post 16 and web 15 hold the tooth against rotation and to the backing.

It will be noted in Figures 5 and 6 that the post hole 11 and planes 8 and 9 of the tooth are inclined to the long axis of the tooth. The plane 8 being given a greater inclination in this embodiment than is shown in Figures 1 and 2.

In Figures 7 and 8 I have shown my invention embodied in a posterior tooth and for convenience of reading the drawings I have used the same reference numerals that are used on the other figures of the drawings as these are substantially the same in both anterior and posterior teeth, from which it will be understood that my invention comprehends anterior and posterior teeth.

In the claims the term "body" is to be understood as including an anterior and a posterior tooth.

What I claim is:

1. An artificial tooth comprising an integral porcelain body, a root and a lingual overhang portion, two bearing faces on the occlusal end of the overhang portion in different horizontal planes extending at substantially right angles to the long axis of the tooth, a mortise intersecting the overhang portion between said faces and extending labially into the body.

2. An artificial tooth comprising an integral porcelain body, a root and a lingual overhang portion, two bearing faces on the occlusal end of the overhang portion in different horizontal planes extending at substantially right angles to the long axis of the tooth, a mortise intersecting the overhang portion between said faces and extending labially into the body, and a slot opening said mortise to the plane of one of said bearing faces.

3. An artificial tooth comprising an integral porcelain body, a root and a lingual

overhang portion, two bearing faces on the occlusal end of the overhang portion in different horizontal planes extending at substantially right angles to the long axis of the tooth, a mortise intersecting the overhang portion between said faces and extending labially into the body, and a slot of less diameter than the mortise opening said mortise to the plane of one of said faces.

4. An artificial tooth comprising an integral porcelain body, a root and a lingual overhang portion, two bearing faces on the occlusal end of the overhang portion in different horizontal planes extending at substantially right angles to the long axis of the tooth, a mortise intersecting the overhang portion between said faces and extending labially into the body, and a bearing face extending from one of said surfaces to the other and disposed in the direction of the long axis of the tooth.

5. An artificial tooth comprising an integral body, a root and a lingual overhang portion, two bearing faces on the occlusal end of the overhang portion in different horizontal planes extending at substantially right angles to the long axis of the tooth, a mortise intersecting the overhang portion between said faces and extending labially into the body, and a bearing face extending from one of said surfaces to the other and disposed in the direction of the long axis of the tooth, and a backing having bearing surfaces complementary to the bearing surfaces of the tooth structure.

In testimony whereof I affix my signature.

LAFAYETTE D. PICKERING.
